UNITED STATES PATENT OFFICE.

SALMON W. PUTNAM, JR., OF FITCHBURG, MASSACHUSETTS.

IMPROVEMENT IN NUT-TAPPING MACHINES.

Specification forming part of Letters Patent No. 140,727, dated July 8, 1873; application filed April 11, 1873.

To all whom it may concern:

Be it known that I, SALMON W. PUTNAM, Jr., of Fitchburg, of the county of Worcester and State of Massachusetts, have invented a new and useful Improvement in Nut-Tapping Machines; and do hereby declare the same to be fully described in the following specification and represented in the accompanying drawings, of which—

Figure 1 is a top view; Fig. 2, a rear elevation; Fig. 3, a horizontal section; and Figs. 4 and 5 are vertical sections, of a nut-tapping machine as improved by me. Fig. 6 is a side view; Fig. 7, a front-end view; Fig. 8, a rear-end view; and Fig. 9, a longitudinal section, of the "tubular bushing" to be hereinafter explained. Fig. 10 is a top view, and Fig. 11 a side view, of the tapping-tool.

My invention relates, first, to the combination of an eccentric carrier or tube with the tapping-tool arbor, its driving-gear, pinion, and head-stock; second, to three arbors, their driving-gears and pinion arranged together and with the head-stock, in manner as hereinafter explained; third, to the combination of an auxiliary gear and its carrier with two of the arbors and their driving-gears and eccentric carriers; fourth, to a tubular bushing for the tapping-tool and its arbor—that is, to such bushing constructed with a prismatic holder at its inner end, and with a hole arranged in its side, all being as and for use as hereinafter explained; fifth, to the bushing so made, the arbor and the clamp-screw arranged as set forth and shown.

In the drawings, A denotes a head-stock, provided with three arbors, B, C, and D, arranged within it and parallel to each other, as shown, there being a driving-gear, E, F, or G, fixed on the rear end of each of said arbors. The two outermost gears E G lap over and are disposed in the rear of, and each is of greater diameter than, the other gear F. A single driving-pinion, H, fixed upon a shaft, I, provided with driving-pulleys K K' K'', is arranged between the gears E and G, and extends underneath the gear F and engages with the three gears. Each of the arbors goes lengthwise through, so as to be supported by and be capable of being revolved within a cylinder or tube, L, whose bore is eccentric to its

periphery. Such cylinder or eccentric carrier, as it may be termed, is supported in a cylindrical bearing, m, in the head-stock, and is provided with a handle, n, which extends from it in manner as shown.

By taking hold of the handle and moving it so as to revolve or turn the eccentric carrier in the head-stock, the driving-gear of its arbor may be thrown out of or be moved into engagement with the driving-pinion. Thus it will be seen that when it may be desirable to arrest the motion of either of the arbors, this may be done without at the same time causing any stoppage of motion of the others. This arrest of motion of either arbor has to be effected whenever the shank of its tapping-tool may have become filled with nuts, in which case the tapping-tool has to be withdrawn from its holder for the nuts to be discharged from the shank of the tool.

But one tapping-tool is shown in the drawings. Each of the arbors are to be supposed to be supplied with one. This tool is shown at M, constructed in the ordinary way, except that its shank b at its rear part is provided with a prismatic tenon, c, to enter a corresponding cavity or holder, d, made in the rear end of a tubular bushing, N, in whose side a hole, e, is formed to receive a set-screw, f, when screwed laterally into the arbor.

The bushing inserted in the arbor, and formed as shown, will be held therein by the set-screw, which, going through the hole e and being screwed against the shank b, will operate not only to hold the bushing but the tapping-tool in place in the arbor. The tenon of the shank and the corresponding holder in the bushing operate to prevent the shank from turning within the bushing. As the tapping-tools vary in size according to the nuts required to be made, each tool, in order to properly centralize it with the arbor, has to have its bushing to fix it in the arbor.

The middle arbor with its gear will run at a greater speed than either of the other arbors, thus enabling nuts with finer screw-threads to be cut at the same time that nuts are being made or tapped by the tools of the other or larger arbors. Furthermore, as it may be desirable to cause the two larger arbors to revolve at one and the same time in opposite di-

rections in order for left screw-nuts to be tapped by the tool of one, while right screw-nuts may be in the act of being tapped by the tool of the other, there is pivoted on the shaft of the driving-pinion a pendulous or radial arm, O, slotted, as shown at *h*, and carrying upon a pivot, *i*, (projecting from it,) a small gear, P, engaging with the pinion, and arranged in the plane of the two larger gears E and G. A clamp-screw, *k*, goes through the slot *h* and screws into the head-stock.

By turning the eccentric carrier L of either arbor B D, so as to throw the driving-gear of such arbor out of engagement with the driving-pinion, and next moving the auxiliary gear P into engagement with the said driving-gear, the rotary motion of one arbor will be in a direction opposite to that of the other while the two may be in movement.

I claim as my invention in the above-described nut-tapping machinery as follows, viz.:

1. The combination, as specified, of the ec-

centric carrier L with the tapping-tool arbor, the head-stock A, driving-gear G, and pinion H, all being arranged as represented.

2. The combination of the auxiliary gear P and its slotted carrier or pendulous arm O with the two driving-gears E G and the eccentric carriers L L applied to the head-stock and the arbors of such gears, all being essentially as explained.

3. The tubular bushing N provided with the prismatic mortise or holder *d* and the hole *e* arranged in it, as described.

4. The combination of the bushing N, (so made or provided, viz., with the holder *d* and hole *e*,) the arbor D, and the clamp-screw *f*, all arranged and to operate together and with the tapping-tool, as represented.
